UNITED STATES PATENT OFFICE.

ELMER C. DICEY, OF CHICAGO, ILLINOIS.

CUT-OFF-VALVE GEAR.

SPECIFICATION forming part of Letters Patent No. 322,264, dated July 14, 1885.

Application filed April 6, 1885. (No model.)

To all whom it may concern:

Be it known that I, ELMER C. DICEY, a citizen of the United States, residing at Chicago, in the county of Cook and State of Illinois, 5 have invented a new and useful Automatic Cut-Off-Valve Gear for Steam-Engines, of which the following is a specification.

My invention relates to improvements in steam-engine governors or regulators in which 10 the steam is cut off at different points of the stroke, taking steam at full-boiler pressure at the commencement of the stroke, and cutting off at whatever part of the stroke is necessary to maintain a uniform speed of the engine, 15 the point of cut-off being regulated by the ordinary governor-balls in the manner hereinafter described. I attain these objects by the mechanism illustrated in the accompanying drawings, in which—

20 Figure 1 is a vertical elevation, partly in section, of my improved machine. Fig. 2 is an end view of the vibrating arm D and attachments. Fig. 3 is an end view of the disk B. Fig. 4 is a vertical cross-section of my improved machine.

25 Similar letters refer to similar parts throughout the several views.

To operate my improved governor, the flange e is bolted rigidly to an opening in the 30 steam-chest of an engine. The steam-pipe or stop-valve leading from the boiler is bolted to the flange e'. The pin d' is attached to the valve-rod by a suitable connection rod or link, so as to give the arm D a vibratory motion 35 corresponding in time to the reciprocating motion of the valve of the engine when the governor-valve opens, giving a free and unobstructed passage for the steam from the boiler to the engine at the commencement of each 40 stroke. Steam being admitted from the boiler enters the governor in the direction indicated by the arrow in Fig. 4, until it meets the shell E and is distributed above and below the valve, passing down through the upper 45 per and up through the lower disks of the

same. The upper disk is made enough larger than the lower disk to cause the valve to close promptly by the preponderance of pressure on the upper disk on being released in consequence of the wiper d' having passed 50 clear of the tappet e, allowing it and the pin b' to fall back to the central and lowest position. The tappet e is riveted to the rod C and embraced loosely by the slot b in the hollow shaft B, by which motion is communicated to 55 disk B', carrying the pin b', which, in its partial revolution, raises the valve A by pressing upward on the lifter-plate a'. After steam has been admitted to the engine, should the speed increase above that at which the governor is intended to run the balls will rise and lift the rod a' and rack a'', causing the spur-wheel A' to revolve and carry back the rod C and tappet e farther toward the end of the wiper d', allowing the valve to close sooner, 60 so as to cut off the steam earlier in the stroke of the engine until the engine is reduced to its normal speed. The angle of the tappet e causes the steam to be cut off earlier or later in the stroke as the tappet e is moved 65 to or from the wiper d'.

Having thus described my invention, what I claim, and desire to secure by Letters Patent, is—

1. The combination, in a steam-engine governor, of the vibrating yoke D, wiper d', tappet e, crank-disk B', and lifter-plate a', substantially as described, and for the purpose set forth.

2. The combination, in a steam-engine governor, of the double puppet-valve A, rod a', having rack a'', the spur-gear A', rod C, carrying tappet e, the wiper d', crank-disk B', having pin b', and the lifter-plate a', substantially as shown and described.

ELMER C. DICEY.
